UNITED STATES PATENT OFFICE.

EDWARD D. WESTRIP, OF MYERSTOWN, AND RALPH McCARTY, OF LEBANON, PENNSYLVANIA.

PIPE-THREADING MACHINERY.

No. 873,834.

Specification of Letters Patent.

Patented Dec. 10, 1907.

Application filed January 28, 1905. Serial No. 243,009.

To all whom it may concern:

Be it known that we, EDWARD D. WESTRIP, of Myerstown, Pennsylvania, and RALPH McCARTY, of Lebanon, Pennsylvania, both 5 citizens of the United States, have invented certain new and useful Improvements in Pipe-Threading Machinery, of which the following is a specification.

Our invention relates to pipe-threading 10 machinery and more especially to means for automatically controlling the dies so as to cut threads of any desired length, and further relates to various devices incidental to said means.

15 In the accompanying drawings, Figure 1 is a front elevation of a pipe-threading device embodying our improvements; Fig. 2 represents a portion of the device shown in Fig. 1 with the parts in changed relations; 20 Fig. 3 is a top plan and perspective view of a portion of the mechanism shown in Fig. 1, the die-head being cut away and removed to show clearly mechanism contained within it; Fig. 4 is a section along the line *a—a* on Fig. 25 1. Moreover in viewing this figure, it should be compared with Fig. 3—because it shows the same parts 24, 25, and 26 as Fig. 3 in the same position of adjustment and viewed from the same point of view, that is from 30 above. This figure differs however from Fig. 3 in that it is a non-perspective and partly sectional view of the parts in question, and in the further particular that it shows the character and relative location of 35 the recess 30 in the wall of the die-head 1. This recess was purposely omitted from Fig. 3 in order not to encumber the drawing. If supplied however it would occupy the same relative position to the parts 24, 25, 26 etc. 40 as that shown in Fig. 4. Fig. 5 is a view in elevation looking in the direction of the arrow at the parts shown in Fig. 4; Fig. 6 is a section through the axis of the shaft 24, and along the line *b—b* in Fig. 3; Fig. 7 is a horizontal section along the line *c—c* of Fig. 6; 45 and Fig. 8 is a horizontal section along the line *d—d* of Fig. 6.

In the accompanying drawings our improvements are shown in connection with 50 one type of pipe-threading machine, but it is to be understood that our improvements are not limited to this peculiar type of machine, but may be used in other types, and we are not to be understood as limiting ourselves in this regard.

Describing now the drawings in which

the same reference characters designate corresponding parts throughout, and in which some of the forms only, which our improvements may take, are illustrated; the numeral 60 1 designates a stationary die-head upon which is rotatably mounted the cam-ring 2, by the rotation of which the position of the dies 3 is governed. It will be unnecessary to go into the detailed construction of 65 these parts; suffice it to say that the cam-ring is provided on the inside with cams (not shown), which operatively engage the dies located in slots in the stationary die-head and serve to project said dies into their 70 cutting position when the ring is rotated sufficiently to the right, and to withdraw said dies when the ring is rotated to the left. The means for so operating the cam-ring comprises a bracket 5 on the die-head, to which 75 5 is pivotally secured the lever 6 by the pivot 7; also the bracket 8 secured to the cam-ring, to which the threaded rod 9 is pivoted by means of the plain swivel-nut 10 through which the rod passes, and within which it 80 can be rotated on itself. A collar 13 on this rod, in connection with the head 12 located on the other side of the plain swivel-nut, prevents the rod from sliding through the nut, but does not interfere with its rotation 85 therein. The lever 6 and the rod 9 are pivotally connected by the threaded swivel-nut 11 secured to the lever,—the threads on the end of the rod co-acting with the threads in the swivel-nut. An abutment 42 is pro- 90 vided on the lever 6, and is arranged to engage against the rod 9 when the three pivotal connections 10, 11 and 7 are in substantial alinement. The effect of this is that the thrust of the pipe as it rotates under the 95 dies, tending as it does to rotate the cam-ring to the left, is unable to so rotate it when the lever is seated against the rod, because all three pivotal connections being alined the thrust of the rod on the lever acts through 100 the fulcrum of the lever, and consequently has no leverage to raise it out of its engaged position against the rod; the ring is therefore effectively locked against rotation due to the thrust of the pipe on the dies.

105 By turning the threaded rod 9 one way or the other the distance between the pivots 10 and 11 can be adjusted, and consequently the degree of rotation of the cam-ring and of the projection of the dies, regulated.

110 Describing now the features belonging particularly to our present improvements,

they may be said to comprise in a general way, first, automatic operating means for raising the lever 6, and consequently withdrawing the dies 3 at a given instant; second, 5 means for locking, for example, the lever 6 by engaging same with a stop which prevents the automatic operating means from acting; third, means comprising a finger adjustably supported in the path of the pipe 10 as it is fed between the dies, and operatively connected with the aforesaid stop, whereby when a given length of thread has been cut the end of the pipe presses against the adjustable finger in its path, moves the above mentioned stop out of engagement with its interlocking part on the lever, and allows the automatic operating means to raise the lever and thereby withdraw the dies and stop their threading action; and, fourth, means 15 for wholly withdrawing the finger out of the path of the pipe in order that the latter may be fed freely through the die-head and cut off at the desired length. Describing now more particularly these devices as illustrated 20 in the drawings: The automatic lever or cam-ring operating means comprises the spiral spring 18 attached at 19 to a fixed part of the machine, and at the other end connected, by a chain passing over the pulley 25 16, with the end of the upright 14 secured to the lever 6. In Fig. 1 the lever is supposed to be held down forcibly and the spring 18 to be under tension, whereas in Fig. 2 the lever has been released and the spring 30 35 allowed to act, with the result that the lever has been raised into the position shown, the cam-ring rotated to the left, and the dies withdrawn from the pipe.

The means for preventing the automatic 40 operating means from coming into action comprises a lug 22 on the lever 6, which is adapted to engage under a stop 23 secured to the rock-shaft 24. This rock-shaft extends through the die-head in which it has its bearing, and is provided at its lower end with a connection 25 in which is adjustably mounted the finger 26; the finger being adapted to project into the path of the pipe when the stop mounted on the other end of the rock-shaft 45 engages the lug on the lever, and when pressed by the pipe to rotate the rock-shaft and to disengage the stop 23 from the lever and to allow same to be pulled up by the spring 18. The finger 26 is adjustably supported as stated by providing same at its 50 lower end with flanges which are adapted to engage the dovetail groove 27 in the extension 25 on the rock-shaft. Screw threads are provided at the base of the finger 26 with 55 which the nut 29 engages, and when screwed down against the top of the groove is effective to hold the finger rigidly in any position of adjustment along the groove. By having the finger 26 adjustably mounted it can be 60 located at various positions along the direc-

tion of the pipe feed, and will control, depending upon its position, the length of thread cut on the pipe, since the dies will keep on cutting until the end of the pipe strikes the finger. 70

The means for allowing the finger to be withdrawn from the path of the pipe, in order that the latter may be fed through the die-head and cut off at the desired length, comprises the recess 30 in the die-head, into 75 which by rotation of the rock-shaft the finger 26 and the adjustable support 25 can be recessed or withdrawn. This is accomplished automatically by the action of the spiral spring 35 acting on the end 36 of the pivot-pin 33 of the handle 32, and which, when unopposed, rotates the finger 26 into the recess in the die-head. The means for opposing this action of the spring 35 comprises the handle 32, pivoted to the collar 34 secured 80 to the upper end of the rock-shaft, and a raised stop 31 secured to the die-head, and arranged to engage the side of the pivoted handle 32 when the rock-shaft has been rotated to a position where the finger 26 projects into the path of the pipe. By raising the pivoted handle 32, so that it no longer engages the fixed stop 31, the spring 35 is allowed to act and rotates the rock-shaft to withdraw the finger into the recess. 95

It will be noted that as the threaded rod 9 is adjusted so as to rotate the cam-ring more and more to the right, that the threaded rod will become more and more depressed, and consequently, since the lever follows the rod, the lug 22 on said lever will correspondingly occupy a lower and lower level. We have therefore provided means for regulating the position of the stop 23 on the rock-shaft, which, it will be remembered, engages with the lug on the lever, to correspond with the varying positions of the latter. This we accomplish very effectively by providing a sleeve 38 which is adapted to fit loosely over the threaded end of the rock-shaft. This sleeve bears the stop 23, and is prevented from rotating on the rock-shaft by the spline 39, while the hand nuts 40 and 41 on either side of the sleeve allow the same to be quickly adjusted at any position along the 100 threaded end of the rock-shaft. 110

Having thus described our invention what we claim is:—

1. In a pipe-threading machine, the combination of a die-head provided with die-slots; dies located in said slots and operatively connected with a rotatable cam-ring and governed thereby; cam-ring mechanism comprising said cam-ring and means for rotating it into and out of the working position 120 which it occupies when the dies are cutting; locking means comprising a stop secured to a rock shaft and a part in said cam-ring mechanism which when engaged lock the cam-ring in its working position; said rock 125 shaft 130

- shaft; a finger adapted to project into the path of the pipe-feed and secured to said rock shaft, and adapted when pressed by the moving pipe to move the aforesaid stop on the rock shaft out of its engaged position; and automatic means adapted to shift the cam-ring automatically out of its working position when the parts comprising the locking means are disengaged.
- 5 2. In combination, a die-head having an opening therein in the direction of the pipe-feed to permit the complete passage therethrough of a pipe; dies projecting from the die-head into said opening and movable into and out of cutting position to thread the pipe; die-locking means adapted when engaged to lock the dies in cutting position; a rock-shaft; a finger on said shaft rotatable therewith into and out of the path of the pipe- 10 feed and connected with the die-locking means, said finger operating when pressed by the pipe, to disengage said locking means; a spring acting on the rock-shaft normally to rotate the finger against the direction of the pipe-feed and out of its path; and a releasable stop adapted to stop rotation of the rock-shaft at the point where its finger is in the path of the pipe, until said stop is released.
- 15 3. In a pipe-threading machine, the combination of a die-head; a cam-ring rotatably mounted on said die-head; dies operatively connected with the cam-ring and governed by the rotation thereof; an arm secured to the die-head by a pivotal connection; a second arm secured to the cam-ring by pivotal connection; a pivotal connection between said arms; an abutment on the first arm ar- 20 ranged to engage the second arm when said arms are positioned with their three pivotal connections in substantial alinement; adjusting means adapted to vary the length of the second arm between its respective pivotal connections with the first arm and the cam-ring; a movable stop adapted to engage one of said arms and to lock the cam-ring in the working position which it occupies when the dies are cutting; a support for said stop; means for adjusting the position of said stop on its support; and means operatively connected with said stop and adapted to contact with the moving pipe to disengage the movable stop.
- 25 4. In combination, a die; a rotary cam adapted to control said die; an arm secured to a stationary part by a pivotal connection; said stationary part; a second arm pivotally connected with the rotary cam; a pivotal connection between said arms; locking means comprising a movable stop adapted to engage one of said arms and to lock them in the position which they occupy when the die is cutting; and a finger connected with said movable stop and projecting into the path of the article being threaded and adapted when pressed by said article to disengage the stop.
- 30 In testimony whereof, we have signed our names to this specification, in the presence of two subscribing witnesses.
